UNITED STATES PATENT OFFICE.

ROMEO J. TRICE, OF EUFAULA, OKLAHOMA.

MUSIC-LEAF TURNER.

942,949.

Specification of Letters Patent. Patented Dec. 14, 1909.

Application filed November 14, 1908. Serial No. 462,639.

To all whom it may concern:

Be it known that I, ROMEO J. TRICE, a citizen of the United States, residing at Eu-
faula, in the county of McIntosh, State of
Oklahoma, have invented certain new and
useful Improvements in Music-Leaf Turn-
ers; and I do hereby declare the following to
be a full, clear, and exact description of the
invention, such as will enable others skilled
in the art to which it appertains to make and
use the same.

The invention relates to a music leaf
turner and more particularly to an auto-
matic music leaf turning device.

The primary object of the invention is
the provision of a music leaf turner having
spring actuated mechanism for automatic-
ally turning successively music leaves and
means for reversing said mechanism where-
by the previously turned music leaves will
be reset.

Another object of the invention is the pro-
vision of a music leaf turner which is adapt-
ed to be mounted at the front of a pianoforte
and having mechanism adapted to actuate
music leaf supporting arms for turning
music leaves connected to said arms said
mechanism being controlled by a main wind-
ing spring, a manually operable lever to
shift the mechanism whereby the arms sup-
porting the leaf music will be successively
moved so as to turn one leaf after the other
at the will of the operator and means for re-
setting the said mechanism.

With these and other objects in view the
invention for example, consists in the con-
struction, combination and arrangement of
parts as will be hereinafter more fully de-
scribed and as illustrated in the accompan-
ying drawings which disclose the preferred
form of embodiment of the invention. It is
to be understood however, that changes, varia-
tions and modifications may be made
such as come properly within the scope of
the claims hereunto appended without de-
parting from the spirit of the invention.

In the drawings:—Figure 1 is a front eleva-
tion of the invention. Fig. 2 is a top plan
view thereof. Fig. 3 is a longitudinal sec-
tional view through the casing to show the
position of the interior mechanism. Fig. 4
is a further top plan view with the top of
the casing broken away. Fig. 5 is a vertical
sectional view on the line 5—5 of Fig. 4.
Fig. 6 is a further sectional view on the line

6—6 of Fig. 4. Fig. 7 is a top plan view
with the top of the casing removed showing
the mechanism reversed. Fig. 8 is a plan
view of the combined ratchet and cog gear.

Similar reference characters indicate cor-
responding parts throughout the several
views in the drawings.

In the drawings, the numeral 10 design-
ates generally the casing or housing of the
music leaf turner comprising a base plate
11, front and rear walls 12 and 13, end walls
14 and a top plate 15 upon which latter are
mounted vertical spaced uprights 16 having
upper and lower cross strips 17 and 18 re-
spectively connected thereto and which form
a back frame or rest for the music sheet.

Centrally in the top plate 15 and extend-
ing from the rear edge thereof is an open
slot 19 with which aligns a bearing groove
20 formed in the bottom or base plate 11 and
mounted in the said groove and passing up-
wardly vertically through the open slot 19
is a rotary shaft 21 having outwardly pro-
jecting parallel upper and lower arms 22 to
which is suitably connected a music sheet.
Surrounding the said shaft 21 is a hollow
shaft 23 the same being cut away and hav-
ing outwardly projecting parallel arms 24
to which is adapted to be connected a music
sheet. Also surrounding the hollow shaft 23
is another hollow shaft 25 the same being
cut away as at 26 to permit the move-
ment of the arms 22 and 24 upon the rota-
tion of the shaft carrying the same and
which hollow shaft 25 carries outwardly
projecting supporting arms 27 to which is
adapted to be connected a music sheet.

Fixed to the lower end of the shaft 21 is
a broad toothed cog gear or wheel 28 and to
the shafts 23 and 25 are fixed toothed gears
or cog wheels 28' and 29 respectively.

Within the casing 10 are rigidly mounted
parallel plates or arms 29' having pivotally
connected thereto the ends of a U-shaped
member 30 the same supporting a vertically
disposed key winding shaft 31 projecting
upwardly through an elongated slot 32
formed in the top plate 15 of the casing.

Fixed to the key winding shaft 31 is a
winding drum 33 to which is connected one
end of a main spring 34 the opposite end
thereof connected to a vertical pin or post
35 carried by the arms 29' and adjacent the
winding drum within the casing. Loosely
mounted upon the winding shaft 31 below

the winding drum 33 is a cog gear 36 having formed in its upper face ratchet teeth 37 in engagement with a spring pawl 38 carried by the winding drum and which pawl is 5 adapted to ride over the ratchet teeth 37 when the main spring 34 is being wound upon the winding drum by the key winding shaft and during the unwinding of the main spring 34 the winding drum 33 is 10 locked to the cog gear or wheel 36 by the said pawl to automatically turn the music sheet as will be hereinafter more fully described.

Pivottally connected to the U-shaped member 30 are links in the form of flat plates 39 which latter support a vertical short shaft 40 forming a bearing shaft for a rotatable cog gear or wheel 41 meshing with the cog gear or wheel 36 on the key winding shaft. 15 Pivottally connected to the links 39 by engagement with the bearing shaft 40 are rocking plates 42 the latter fulcrumed as at 43 to the rigid arms 29' and carrying at their free ends a squared vertical shaft 44 having 20 fixed thereto a cog gear 45 and above the latter is slidably mounted on the said shaft 44 a gear wheel 46 the latter normally held contiguous with the cog gear 45 by a tension spring 47 and which gear 46 is adapted to 25 be thrown into mesh with the gears 28, 28' and 29 respectively for rotating the same to cause movement to the arms supporting music sheets for turning the latter in successive order. Said cog gear 46 is provided 30 on one side with a collar 48 engaged by a forked extremity 49 of a rocking lever 50 the latter pivoted as at 51 to a bearing 52 which latter is pivoted as at 52' to a bracket 52" mounted on the bottom or base plate of 35 the casing and which lever is adapted to raise and lower the gear wheel 46 into engagement with the gears 28, 28' and 29 fixed to the shafts carrying the arms supporting the music sheets. To lock the rocking lever 40 in its thrown position there is provided a pivotal dog 53 having an extension 54 connected to a rod 55 the latter connected to a spring controlled finger piece 55' pivoted to the shifting lever. This finger piece 55' normally holds the dog 53 in locking engagement with a notched post 56' during the shifting movement of the driving gears. Projecting outwardly from the U-shaped member 45 is an arm 56 carrying a set screw handle 58 in various adjusted positions and which lever is adapted to be actuated by the operator for reversing the gear mechanism by bringing the cog wheel or gear 41 into 55 engagement with the cog gear 28 which will reset the arms supporting the music sheets after being turned.

To connect the music sheets to the arms 22, 24 and 27 there are provided clips 59. To 60 maintain the shafts 21, 25 and 23 remov-

ably connected to the casing there are provided pivotal locking members 60 whereby the said shafts can be easily withdrawn or detached from the casing at the will of the operator.

To prevent the turning of the music sheets supported by the arms 22, 24 and 27 prior to being actuated by the leaf turning mechanism, there is provided a spring controlled pawl 61 which latter is pivoted as at 62 to 70 one end of an angular-shaped arm or piece 63 containing a curved slot 64 centrally thereof in which works the shaft 44 upon the shifting of the gear 45 (see Fig. 6) and this angular arm or piece 63 is vertically 75 so slidable upon stationary posts or pins 65 as to permit the said locking pawl 61 to engage the teeth of the gears 28, 28' and 29 respectively should the shifting lever 50 be actuated to bring the gear 46 in the plane of 80 any one of the said gears 28, 28' and 29 to mesh therewith for the subsequent turning of the music sheets.

In operation, presuming that the spring 34 has been wound and that the supporting 90 arms have been swung to the right of the axis of rotation of the shafts carrying the same and to these arms are connected the leaves of a music book and it now being desired to successively turn the leaves at pre- 95 determined intervals, the operator shifts the arm 56 to the right to disengage the gear 41 from the gear 28 and by this gear 41 meshing with the gears 36 and 45, which latter is fixed to the squared shaft 44, the 100 same having slidably mounted thereon the gear 46 which at this moment engages the gear 28, so that by the action of the spring 34, the said train of gears will rotate this gear 28, turning shaft 21 to the left so as 105 to turn the first leaf of the book of music in the same direction. Now should it be desired to turn the second leaf of the book of music, the operator actuates the finger piece 55' to release the pivotal rocking lever 50 and by pressing downwardly upon the same it is caused to rock upon its pivot 52' and in this manner the gear 46 is raised into engagement with the gear 28' and by the action of the spring 34 said gear 28' will turn or rotate the shaft 23, so as to turn the music leaf connected to the supporting arms 24 to the left. When it is desired to turn the last or third leaf of the music book the rocking lever 50, is further depressed to raise the 110 gear 46, into engagement with the gear 29, and in this manner the said last or third leaf is turned to the left upon the rotation of the shaft 25, of the device. When it is necessary to shift the arms to the right the 115 operator shifts the arm 56 to the left, which brings gear 41 into mesh with gear 28 and by the action of the spring 34 the shaft 21 will be caused to turn to the right and by the turning of the supporting arms 22 in 120 125 130

this direction will effect the simultaneous turning of all of the other arms in the same direction.

What is claimed is—

- 5 1. A music leaf turner comprising a plurality of interfitting rotatable shafts, gears fixed to said shafts and arranged in superposed relation to each other, a shiftable train of gearing, means for raising one of said gears of the train into successive engagement with the gears fixed to the shaft, and means for shifting said train of gears to effect alternate meshing of a pair of its gears with one of the shaft gears for reversing the direction of rotation of the shaft, spring wound means for driving said train of gearing, and means for locking said raising means in adjusted position. 50
- 10 2. A music leaf turner comprising a plurality of interfitting rotatable shafts, gears fixed to said shafts and arranged in superposed relation to each other, a shiftable train of gearing, means for raising one of said gears of the train into successive engagement with the gears fixed to the shaft means for shifting said train of gears to effect alternate meshing of a pair of its gears with one of the shaft gears for reversing the direction of rotation of the shaft, spring wound means for driving said train of gearing, means for 60 locking said raising means in adjusted position, and supporting arms projecting from said shaft. 65
- 15 3. A music leaf turner comprising a plurality of interfitting rotatable shafts, gears fixed to said shafts and arranged in superposed relation to each other, a shiftable train of gearing, means for raising one of said gears of the train into successive engagement with the gears fixed to the shaft, means for shifting said train of gears to effect alternate meshing of a pair of its gears with one 70 of the shaft gears for reversing the direction of rotation of the shaft, and means for driving said train of gearing. 75
- 20 4. A music leaf turner comprising a plurality of interfitting rotatable shafts, gears fixed to said shafts and arranged in superposed relation to each other, a shiftable train of gearing, means for raising one of said gears of the train into successive engagement with the gears fixed to the shaft, means for shifting said train of gears to effect alternate meshing of a pair of its gears with one of the shaft gears for reversing the direction of rotation of the shaft, spring wound means for driving said train of gearing, means for 80 locking said raising means in adjusted position, supporting arms projecting from said shaft, and clip means carried by said supporting arms. 85
- 25 5. A music leaf turner comprising a plurality of interfitting rotatable shafts, gears fixed to said shafts and arranged in superposed relation to each other, a shiftable train of gearing, means for raising one of said gears of the train into successive engagement with the gears fixed to the shaft, means for shifting said train of gears to effect alternate meshing of a pair of its gears with one of the shaft gears for reversing the direction of rotation of the shaft, spring wound means for driving said train of gearing, means for 90 locking said raising means in adjusted position, and supporting arms projecting from said shaft.

In testimony whereof, I affix my signature, in presence of two witnesses.

ROMEO J. TRICE.
